J. SCHMIDINGER,
COMBINATION STENCIL.
APPLICATION FILED MAR. 21, 1921.

1,393,170.

Patented Oct. 11, 1921.

By Frederick V. Winters
Attorney.

UNITED STATES PATENT OFFICE.

JOSEPH SCHMIDINGER, OF NEW YORK, N. Y.

COMBINATION-STENCIL.

1,393,170.

Specification of Letters Patent. Patented Oct. 11, 1921.

Application filed March 21, 1921. Serial No. 453,935.

To all whom it may concern:

Be it known that I, JOSEPH SCHMIDINGER, a citizen of Austria, residing at New York, in the county and State of New York, have 5 invented certain new and useful Improvements in Combination-Stencils, of which the following is a full, clear, and exact specification.

This invention relates to stencils or marking tools, and has for its object to provide 10 an improved and simplified form of combination stencil embodying a plurality of marking dies or cutters.

It is the aim of the present invention to 15 provide a circular marking tool or stencil having radiating dies or cutters and anvil or striking heads, one of the latter being disposed diametrically opposite each of the former, and said dies alternating with said 20 striking heads around the entire circumference of the circular tool. Other objects are to provide the tool with means for conveniently holding the same in position while in use, and to connect the cutting dies and 25 striking heads to the body of the tool in such a manner that they may be easily replaced when worn.

The invention will be first hereinafter described in connection with the accompanying 30 drawings, which constitute part of this specification, and then more specifically defined in the claims at the end of the description.

In the accompanying drawings, wherein 35 similar reference characters are used to designate corresponding parts throughout the several views:

Figure 1 is a front elevation of a marking tool or combination stencil constructed 40 substantially in accordance with this invention, the same bearing a series of numeral cutting dies.

Fig. 2 is a section taken diametrically of Fig. 1 on the line II—II thereof.

Fig. 3 is a front elevation of a modified 45 form of tool bearing a series of letter cutting dies, and

Fig. 4 is a section taken diametrically of Fig. 3 on the line IV—IV thereof.

Referring first to Figs. 1 and 2, the marking tool therein shown comprises a ring-shaped body member 1 having an opening 2 through its center and provided with a series 50 of radial sockets 3 in its periphery. Said 55 sockets are preferably threaded internally,

as at 4, to receive the correspondingly threaded ends 5 of radially projecting cutting dies 6 and striking heads 7, which are arranged alternately in said sockets around the entire periphery of the body member 1. 60 One of the striking heads 7 is arranged diametrically opposite each of the cutting dies 6, so that when the tool is in use, there will always be a striking head in position to be hammered upon for driving any selected 65 cutting die into the work.

The front face of the body member 1 may be marked to correspond with the cutting dies at points in line with said dies, as suggested at 8 in Fig. 1. In this instance, the 70 dies bear a series of successive numerals, but it will be understood that any other indicia may be substituted for said numerals, if desired.

The opening 2 through the center of the 75 body of the tool affords a convenient means for supporting or holding the tool in any desired position while using the same for driving any selected die into a piece of work. The threaded connections of the cutting dies and striking heads with the body member 1 permits of the ready substitution 80 of new dies or heads for old ones which may become too much worn to give good service.

As shown in Figs. 3 and 4, the ring-shaped body member 10 may be enlarged to accommodate a large member of cutting dies 11 and striking heads 12, the tool being thus adapted to carry any reasonable number 85 of said dies and heads. The body member 10, being wider than that shown in Figs.

1 and 2, is preferably formed with depressions or cavities 13 at intervals around both faces thereof, the cavities in opposite faces 90 being in alinement, as shown in Fig. 4, to provide convenient means for gripping the tool between the thumb and fingers while 95 in use. The cutting dies and striking heads in this form of the invention may be threadedly connected to the body member 10, as at 14, in Fig. 4, so that they may be removed as already explained in connection with the form of the invention shown in Figs. 1 and 2. The front face of the body member 10 may also bear indicia in line with each cutting die to correspond with the stencil on said die, as in the form of the invention first described. In this instance, the cutting dies may consist of a series of 100 105 110

letters instead of numerals, but variations in the dies may be made without departing from the invention.

In the above description it will be noted that the cutting dies and striking heads are described as threadedly connected to the body member, but I do not limit myself to this construction, for it is obvious that the cutting dies and striking ends may be

5 cast in the body member and serve all purposes as well as the threadedly connected cutting dies and striking heads.

I claim:

1. In a marking tool, the combination with a circular body member, of radiating cutting dies and striking heads arranged alternately about said head with a striking head diametrically opposite each cutting die.
- 15 2. In a marking tool, the combination with a ring-shaped body member having an opening through its center for the purpose specified, of cutting dies and striking heads projecting radially from the periphery of said body member, one of said striking heads being arranged diametrically opposite each of said cutting dies.
- 20 3. In a marking tool, the combination with a circular body member, of radiating cutting dies and striking heads detachably secured to the periphery of said body mem-

ber, one of said striking heads being arranged diametrically opposite each of said cutting dies.

4. In a marking tool, the combination with a body member having radially disposed sockets in its edge, of cutting dies and striking heads detachably fitted in said sockets, one of said striking heads being arranged diametrically opposite each of said cutting dies.

5. In a marking tool, the combination with a body member having internally threaded sockets disposed radially in its edge, of cutting dies and striking heads having threaded end portions to detachably engage in said sockets, one of said striking heads being arranged diametrically opposite each of said cutting dies.

6. In a marking tool, the combination with a body member, of cutting dies and striking heads projecting radially from the edge of said body member, one of said striking heads being arranged diametrically opposite each of said cutting heads, and said body member having registering depressions in its opposite faces at intervals around the same for the purpose specified.

In testimony whereof I have signed my name to this specification.

JOSEPH SCHMIDINGER.
